UNITED STATES PATENT OFFICE.

GEORGE H. ROWE, OF BERWYN, ILLINOIS, ASSIGNOR TO ELECTRO-MAGNETIC TOOL COMPANY, OF CHICAGO, ILLINOIS, A CORPORATION OF ILLINOIS.

ELECTROMECHANICAL DEVICE.

1,024,026.

Specification of Letters Patent. Patented Apr. 23, 1912.

Application filed May 18, 1910. Serial No. 562,109.

To all whom it may concern:

Be it known that I, GEORGE H. ROWE, a citizen of the United States, residing at Berwyn, in the county of Cook and State of Illinois, have invented certain new and useful Improvements in Electromechanical Devices, of which the following is a specification.

My invention relates to an electro-mechanical device of the general character of the devices shown in my Patents No. 894,782, granted July 28, 1908, No. 938,709, granted November 2, 1909, No. 973,216, granted October 18, 1910, and in my application Serial No. 521,732, filed October 8, 1909; and the invention has for its object to provide certain new and improved constructions and arrangements in electro-mechanical devices which will be hereinafter described and claimed.

One of the primary objects of the invention is to provide an air cushion for the striking part which supplements the magnetic connection between the driven element and the driving means.

The invention has for further objects to strengthen, simplify, lighten, and generally to improve the constructions employed when my invention is embodied in a drill or similar percussion device.

The invention is illustrated in the accompanying drawings, in which—

Figure 1 is a fragmentary longitudinal sectional view of an electric drill of the sort best shown in my Patent No. 938,709, above mentioned. Fig. 2 a view in perspective of the reciprocating sleeve. Fig. 3 a longitudinal sectional view of the same. Fig. 4 a sectional view taken on line 4—4 of Fig. 1, looking in the direction of the arrows. Fig. 5 a similar view taken on line 5—5 of Fig. 1. Fig. 6 a side view of the device for supporting the crank shaft bearings of the driving means. Fig. 7 an elevation of one of the pole pieces of the magnet. Fig. 8 a similar view of the tool-holding nose-piece, and Fig. 9 a plain view of the cap piece of the sleeve.

Like characters of reference indicate like parts in the several figures of the drawings.

Referring to the drawings, 10 designates the motor casing and 11 the armature of the motor, portions only of these parts being shown. 12 designates the casing inclosing

the driving gear. 13 is the head of the latter casing and is constructed preferably with a central opening for the ball bearing 14 of the armature shaft 15 of the motor. 16 is a bevel gear on shaft 15 which meshes with a bevel gear 17 on the crank shaft 18. The latter turns in ball bearings 19 which are sustained in the projecting bosses 20 on brackets 21 which are preferably formed integrally with the head 13. This arrangement protects the ball bearings of the crank shaft from dust and dirt.

The ball bearings 14 and 19 are of familiar construction and need not be described in detail.

23 represents the spool of the exciting coil 70 designated by 24. The coil has two pole pieces, pole piece 25 at its inner end and pole piece 26 at its outer end, the latter formed integrally with the steel nose-piece 27. The pole pieces 25 and 26 are preferably formed with the cylindrical extensions 28, to increase their effective area, the extension being preferably slotted at 28^a to prevent eddy currents. Pole piece 26 screws into the steel casing 29 which surrounds the 80 coil 24, casing 29 being lap-joined with casing 12. The tie rods 30 extend through casing 29 into openings 25^a in pole piece 25. The shank 31 of tool holder 32, which carries the drill tool 33 extends through a tool 85 steel socket piece 34 in the nut portion 35 of the nose-piece 27.

Within coil 24 is a sleeve 36, preferably formed with the central openings 37. The sleeve is connected with the crank shaft 18 by a connecting rod 38, the connecting rod being secured to the sleeve by a pin 39, which latter is held in place by cotter pins 40. The pin 39 is also preferably used for securing to the sleeve the cap piece 41, designed to 90 close the inner end of the sleeve so that the armature or plunger 42 is air cushioned. Preferably, the sleeve 36 is formed with the small openings 43 communicating with slots 44 in the outer surface.

41^a is a wedge on the upper surface of cap piece 41 which spreads the ends of one of the cotter pins 40.

It is ordinarily believed that the armature of a solenoid should be made of soft iron because of the magnetic capacity of that metal. I have found by experiment, however, that my armature or plunger 42 gives very good

results from a magnetic point of view when made of hardened tool steel throughout; and the use of this metal makes this part of the device very durable.

5 Preferably, the wires 45, leading into coil 24, pass through bosses 45^a on the pole piece 25. This construction is not claimed herein as it is made the subject matter of claims in my co-pending application, Serial No. 0 521,732, filed October 8, 1909.

Preferably, a thin brass sleeve 46 is interposed between sleeve 36 and pole piece extension 28.

The operation of the device, as above described, is as follows: When the motor is set in operation, sleeve 36 is reciprocated and the magnetic attraction produced by coil 24 causes the armature or plunger 42 to follow the movements of the sleeve the plunger being held in floating relationship with the sleeve and out of contact with the cap piece 41. The plunger is therefore made to strike a series of blows against the shank 31 of the carrier 32 in which the drill tool 33 is mounted. The cap piece 41 forms an air cushion for the plunger 42 at the inner end of the sleeve. This air cushion supplements the magnetic connection between the sleeve and the plunger when the blow is struck in cushioning the parts. It thereby increases the force of the blow and also serves to regulate and govern the magnetic attraction. It likewise prevents the plunger from being accidentally forced back against the driving means for the sleeve and injuring the same. After the supply of current has been shut off from the motor the momentum of the driving mechanism will cause the sleeve to be reciprocated several times. As the magnetic attraction between the sleeve and plunger has ceased, if it happens that the machine is being used in an inverted position with the drill upward, the driving apparatus is likely to be injured by the plunger. 45 The air cushion prevents this.

As modifications of the novel devices, constructions and arrangements will readily suggest themselves to those skilled in this art, I do not limit myself to the several particulars shown and described, except as the same are made limitations on certain of the claims herein. It is obvious, furthermore, that certain of these devices, constructions and arrangements might be applied to forms 55 of electro-mechanical apparatus other than the rock drill shown and described herein.

I claim:

1. In a device of the character described, the combination with a driving element, of 60 a driven element and a magnet for maintaining the latter element in floating and elastic relation with the former; one of said elements comprising a cylinder closed at one end and the other element being fitted into said cylinder so that a relative movement

between said elements results in a compression of air between the same which modifies the effect of said magnet.

2. In a device of the character described, the combination with a driving element, of 70 a driven element and a magnet for maintaining the latter element in floating and elastic relation with the former; one of said elements comprising a cylinder closed at one end and the other element being fitted into said cylinder so that a relative movement between said elements results in a compression of air between the same which modifies the effect of said magnet, said cylinder being formed with a vent. 75

3. In a device of the character described, the combination with a sleeve, a plunger fitted within said sleeve, means for reciprocating the sleeve, means for producing a magnetic connection between said plunger 85 and sleeve, and means which closes one end of the sleeve so as to provide an air cushion which supplements the magnetic connection between said plunger and sleeve.

4. In a device of the character described, 90 the combination with a sleeve, a plunger fitted within said sleeve, means for reciprocating the sleeve, and means for producing magnetic connection between said plunger and sleeve, said plunger being formed at 95 one end with a striking part and said sleeve being closed at the other end so as to provide an air cushion which supplements the magnetic connection between said plunger and sleeve when the plunger strikes its blow. 100

5. In a device of the character described, the combination with driving means, of 105 a sleeve connected therewith at one end, a plunger in said sleeve, means which closes the sleeve at the end connected with the driving means, and means for producing a magnetic connection between said plunger and sleeve, comprising a magnet which is stationary relative to said sleeve and plunger, and which surrounds the same, said sleeve 110 being formed with a vent in the side and a slot, substantially as described.

6. In a device of the character described, the combination with driving means, of a sleeve, a plunger in said sleeve, a coil which 115 is stationary with respect to the sleeve and the plunger, a casing inclosing said coil, and a tool-holding nose-piece provided with an integrally formed ring which screws into said casing and constitutes a pole piece for 120 said coil.

7. In a device of the character described, the combination with driving means, of a sleeve, a plunger in said sleeve, a coil which is stationary with respect to the sleeve and 125 the plunger, a casing inclosing said coil, and a tool-holding nose-piece provided with an integrally formed ring which screws into said casing and constitutes a pole piece for said coil, said ring having an annular ex- 130

tension which intervenes between the coil and said sleeve.

8. In a device of the character described, the combination with driving means, of a 5 sleeve, a plunger in said sleeve, a coil which is stationary with respect to the sleeve and the plunger, a casing inclosing said coil, a tool-holding nose-piece provided with an integrally formed ring which screws into said 10 casing and constitutes a pole piece for said coil, said ring having an annular extension which intervenes between the coil and said sleeve, and a pole piece at the other end of said coil consisting of a ring having a similar integral extension.

9. In a device of the character described, the combination with a sleeve which is closed at one end, means for reciprocating said sleeve, a plunger which is closely fitted 20 in said sleeve so that an air cushion is provided between the plunger and the closed

end of the sleeve, and means for providing a magnetic connection between said plunger and sleeve which sustains the former in floating relation with the latter and out of contact with the closed end thereof. 25

10. In a device of the character described, the combination with a driving element, of a driven element and a magnet for maintaining the latter element in floating and elastic 30 relation with the former; one of said elements comprising a cylinder closed at one end and the other element being fitted into said cylinder so that a relative movement between said elements results in a change in 35 the air pressure between them which modifies the effect of said magnet.

GEORGE H. ROWE.
